UNITED STATES PATENT OFFICE

137,809

DESIGN FOR A CHILD'S EXERCISER OR SIMILAR ARTICLE

Irving R. Heinzel, Chicago, Ill.

Application September 29, 1943, Serial No. 111,234

Term of patent 3½ years

(Cl. D34—15)

To all whom it may concern:

Be it known that I, Irving R. Heinzel, a citizen of the United States and resident of Chicago, in the county of Cook and State of Illinois, have invented a new, original, and ornamental Design for a Child's Exerciser or Similar Article, of which the following is a specification, reference being had to the accompanying drawing, forming part thereof.

In the drawing,
Figure 1 is a side view of a child's exerciser or similar article showing my new design;

I claim:

The ornamental design for a child's exerciser or similar article, as shown.
IRVING R. HEINZEL.
